UNITED STATES PATENT OFFICE.

MAARTEN ADMIRAAL, OF BUSSUM, NETHERLANDS.

STOPPING INDICATOR FOR TRAFFIC PURPOSES.

Application filed March 16, 1921. Serial No. 452,894.

To all whom it may concern:

Be it known that MAARTEN ADMIRAAL, citizen of the Netherlands, residing at Bussum, Raadhuis Straat 16, the Netherlands, has invented certain new and useful Improvements in Stopping Indicators for Traffic Purposes, of which the following is a specification.

This invention relates to an indicating device to be used in railways or in street cars and has for its object to provide improved means for indicating the stopping places.

In street railway traffic the calling out of the stopping places by the conductor leads, as is known, to many troubles and much misunderstanding, which may be avoided by using the device according to the present invention. This device comprises a flexible indicating strip consisting of a series of flexibly connected indicating plates carrying in regular order the names of the different stopping places, adapted to be wound on a drum, and a pair of reversely-arranged driving or feeding devices adapted to be operated by the conductor for imparting a progressive step by step rotary movement to the drum in one direction or the other, for moving the name plates in accordance with the different stopping places.

An embodiment of the present invention is illustrated in the accompanying drawing, in which Fig. 1 is a top view of the device with the cover removed, and Fig. 2 is a cross section on the line A.—B. in Fig. 1.

Referring more particularly to the drawing, 1 indicates a square drum keyed to a shaft 2, which shaft is rotatably supported by bearings 3, attached to the casing 4 of the device, 5 are plates carrying the names of the stopping places in regular order; they are attached to each other by hinges 6 so as to form a continuous, flexible indicating strip, and are adapted to be fed over the drum 1, the sides of which are equal to the height of said plates, so that by turning the drum to the right or to the left the name plates 5 may be moved in one or the other direction.

The turning of the drum 1 to the right is effected by means of a rope pulley 7 loosely mounted on shaft 2 and having a pulling rope 8 trained over its periphery, a pawl 9 being pivotally connected by means of a bolt 10 to said pulley, which pawl engages

the teeth of a ratchet wheel 11, keyed to the shaft 2, so that when said rope is pulled, the pulley 7 will be rotated thereby and, in turn, will rotate shaft 2 and drum 1. A rope 60 pulley 12 with pulling rope 13, and a pawl 14 pivotally connected by a bolt 15 to said pulley 12, all arranged in a like but opposite manner serve to rotate a ratchet wheel 16 and consequently the drum 1 to the left, 65 which may be effected by the disengagement of the pawl 9 from the ratchet wheel 11 and the engagement of the pawl 14 with the ratchet wheel 16.

To that end the pawls 9 and 14 are shaped 70 like angle levers with eyes 17 and 18, and may be lifted from the respective ratchets 11 and 16 by the engagement of said eyes with the levers 20 and 19, respectively. These levers are keyed to a spindle 21, rotated by a hand wheel 22 and supported in bearings 23 attached to the casing 4. When a square drum is utilized, it will be obvious that each ratchet wheel must have four teeth, and that for shifting a name plate 80 from one position to the next the drum and, consequently, the right or left pulley has to be turned 90° and not more. This turning movement may be effected by connecting the pulling ropes 8 and 13 to the pulleys 7 and 12 at the points 24 and 25, respectively, in such a manner that the length of the respective pulling ropes on the pulleys is equal to one quarter of the circumference of said pulleys. 90

It will also be plain, that instead of a square drum, a drum of any other polygonal shape may be used, provided only that the height of the name plates is equal to that of the sides of the drum, that the number of 95 teeth on the ratchet wheels is equal to the number of the sides of the drum and that the length of the pulling ropes on the pulleys is equal to the circumference of the pulley divided by the number of the drum-sides. In order to bring the rope pulleys back into their former position, springs 26 and 27 are connected to the bottom of the casing and fastened by means of ropes 28 and 29 to the respective rope pulleys. 100 105

Brackets 30 are provided for fastening the device at some suitable place in the car, and 31 is a sight-opening in the casing through which the passengers may observe the shifting name plates. 110

On the drawing are shown nine name plates, of which seven may be provided with

the names of the stopping places, the two remaining or end plates being left blank on account of the window or sight opening 21 (which is situated at the right side of the 5 casing 2) and of the stop plate 32. The latter which is in the form of a vertical bar or rib disposed transversely of the flexible element formed by the name plates 5 and to which the bent ends of the two end plates 10 are fastened, as represented in Fig. 2, is designed to engage said drum and thus prevent the turning of the drum when the third plate from the left has reached the sight opening 31.

15 Now the operation of the device consists only in the pulling of the ropes 8 or 13 by the conductor, when starting for the next stopping place.

20 Fig. 2 shows the pawl 9 engaged with ratchet 11, the eye 17 of said pawl being disengaged from the lifting lever 20; while the pawl 14 is disengaged from ratchet 16, its eye 18 being engaged by the lifting lever 19.

25 When a pull is exerted on rope 8, the pulley 7 will be rotated, the spring 26 will be put under tension, the pawl 9 will turn the ratchet wheel 11 one tooth further and the drum will rotate to the right, so that the 30 name of the next stopping place will appear before the opening 31. When the rope is released the spring 26 returns the rope pulley 7 to its former position and as the pawl 9 slips over the ratchet wheel 11, the 35 drum 1 and consequently also the respective name plate will be held in their proper position.

The next pull will have the same result 40 and will bring the succeeding indicating plate opposite the sight opening, and so on, until the last stopping place is reached and the stop plate 32 runs against the drum. Before starting the return trip, the hand-wheel 22 is turned so far to the right, that 45 the lifting lever 19 is disengaged from the eye 18 of pawl 14, while the other lever 20 is engaged with the eye 17 of pawl 9 and lifts the latter out of engagement with ratchet 11; the pawl 14 released from lever 50 19 dropping into engagement with ratchet 16.

Now pulling the rope 13, the device will be operated in the same manner but the drum and the name plates will move in the opposite direction.

55 Although the drawing shows nine indicating plates to be used for seven stopping places, the device may comprise any other suitable number of plates, as the number used is only limited by the space available 60 within the casing for piling up the different plates.

Having now particularly described and ascertained the nature of my said invention I declare that what I claim is:

65 1. An indicating apparatus of the char-

acter described, comprising a drum over which an indicating strip is adapted to pass; and mechanism for imparting an intermittent, step-by-step rotary movement in either direction to said drum, said mechanism embodying a pair of ratchets connected with the drum, one for each direction of movement, a pawl associated with each ratchet to drive the same, a rocking spindle, and a pair of levers carried by said spindle to lift either pawl out of engagement with its respective ratchet.

2. An indicating apparatus of the character described, comprising a feeding drum over which an indicating strip is adapted to pass; and mechanism for imparting an intermittent, step-by-step rotary movement in either direction to said drum, said mechanism embodying a pair of separate driving units each complete in itself, one unit for each direction of movement and located at each side of the drum, and both units operating immediately upon said drum, each unit including an operating member individual thereto and a member engageable by said operating member, and a single device for lifting either operating member out of such engagement to render the corresponding driving unit inactive.

3. An indicating apparatus of the character described, comprising a drum over which an indicating strip is adapted to pass; a shaft on which said drum is keyed; a pair of ratchets keyed to said shaft; a pair of two-armed pawls, one individual to each ratchet, for driving said shaft and drum in either direction; a lever associated with each pawl and engageable with one arm thereof to rock the same and thereby disengage the other arm of the pawl from the respective ratchet; and an operating element whereon said levers are so arranged as to rock only one pawl at a time.

4. An indicating apparatus of the character described, comprising a drum over which an indicating strip is adapted to pass; a shaft on which said drum is keyed; a pair of loose pulleys on said shaft; a flexible operating element for each pulley; a pair of reversely-arranged driving connections between said pulleys and shaft for transmitting the rotation of the former to the latter; and means for simultaneously throwing in one driving connection and throwing out the other.

110 5. In a stopping indicator, the combination of a shaft; an angular drum keyed to said shaft; a series of name plates carrying the names of the successive stopping places in regular order, said plates being 115 flexibly connected to each other and adapted to be moved by rotating said drum, and two ratchet gearings for rotating said shaft and drum in opposite directions, each gearing comprising a ratchet wheel keyed to 120

said shaft, a pair of loose pulleys on said shaft, a pawl pivotally connected to each pulley, said pawls adapted to be alternately engaged and disengaged with said ratchet

5 wheels, and means for imparting an oscillating movement to said pulleys and pawls, to cause a progressive step by step movement of

the ratchet wheel which is engaged at that time by its pawl for moving the drum and the name plates in regular order in accordance with the different stopping places. 10

In testimony whereof I affix my signature.

MAARTEN ADMIRAAL.
